Primary Examiner — David G Muller*(74) Attorney, Agent, or Firm* — Fishman Stewart PLLC**CLAIM**

The ornamental design for a vial, as shown and described.

DESCRIPTION

FIG. 1 is a perspective view of the front of a vial showing my new design;

FIG. 2 is a front elevational view thereof;

FIG. 3 is a side elevational view thereof;

FIG. 4 is a bottom elevational view thereof; and,

FIG. 5 is a top elevational view thereof.

The features shown in broken lines depict portions of the vial that form no part of the claimed design.
